CLAIM

The ornamental design for an air intake plenum assembly, as shown and described.

DESCRIPTION

FIG. 1 is a perspective top view for an air intake plenum assembly showing my new design;

FIG. 2 is a perspective bottom view thereof;

FIG. 3 is a top view thereof;

FIG. 4 is a right side view thereof;

FIG. 5 is a bottom view thereof;

FIG. 6 is a left side view thereof;

FIG. 7 is a front view thereof;

FIG. 8 is a back view thereof;

FIG. 9 is a perspective view showing the air intake plenum manifold in with additional plenum ducting and hardware thereof; and,

FIG. 10 is a left side cross sectional view that is cut through the middle of the air intake plenum assembly.

The broken lines in FIG. 9 depict environmental subject matter only and form no part of the claimed design.
